(57) **CLAIM**

The ornamental design of a section, as shown and described.

DESCRIPTION

FIG. 1 is an end view of a section;

FIG. 2 is an inverted perspective view of the section shown in FIG. 1 showing the left side view and bottom view; and, FIG. 3 is a perspective view of the section shown in FIG. 1 showing the right side view and the top view.

The end view not shown is a mirror image of the end shown in FIG. 1 and the section is of indefinite length.

1 Claim, 1 Drawing Sheet Fig. 1
